UNITED STATES PATENT OFFICE.

CARL HOFFMAN, OF ALLENTOWN, PENNSYLVANIA.

LOCK.

1,388,711.

Specification of Letters Patent. Patented Aug. 23, 1921.

Application filed July 16, 1920. Serial No. 396,695.

To all whom it may concern:

Be it known that I, CARL HOFFMAN, of Allentown, in the county of Lehigh and State of Pennsylvania, have invented certain new and useful Improvements in Locks; and I do hereby declare the following to be a full, clear, and exact description of the invention, such as will enable others skilled in the art to which it appertains to make 10 and use the same.

My invention relates to locks and more especially to the type wherein the locking member also functions as a latching element, and the object of my invention is to provide 15 a simple and highly efficient device of the character stated in which the lock-latch may be operated from inside the door by a handle on the bolt operating spindle which is capable of being moved into and out of 20 operating position and of being locked in both positions; in which the lock-latch is operable from outside the door by a key which must first be turned in one direction to release the spring held bolt operating 25 spindle so that it will come into a position to be turned by the key after the latter has been moved to actuate tumblers and an apertured plate through which the key must be inserted to reach the spindle; and in 30 which the parts are placed in inoperative position by the key from the outside by first slightly turning the key so that its extreme end can push the spindle inwardly, bringing the bit of the key into engagement with 35 a stop to move it into the path of the spindle, and then by reverse movement of the key moving the tumblers and guard plate so that the spindle may not be reached except upon manipulation of the parts by a proper 40 key.

In the drawings, Figure 1 is a view in perspective of a portion of a door and its casing with my improved lock applied, the view being from inside the door. Fig. 2 is a 45 horizontal sectional view of the lock. Fig. 3 shows the lock with part of the casing removed and discloses the guard plate actuating slide and the spindle stop. Fig. 4 is a perspective view showing the guard plate, 50 support, guard plate actuating slide, and tumblers, all in dismantled form. Fig. 5 is a face view of the lock-latch with its immediately related actuating members. Fig. 6 is a perspective of a key.

55 At 1 I have indicated the lock-latch hous-

ing and at 2 the casing for the control mechanism, the casing being set within a cut out of the door 3 while the housing is attached to the door in known manner. Within the housing is a lock-latch which includes 60 a locking member 4 attached to a plate 5 having the usual branches 6 which form the means to which power is applied to move the lock-latch against the tension of a spring 7. The plate is also provided with a second spring 8 by which the spindle 9 is normally maintained in operating position, the spring engaging a laterally extending arm 10 of the spindle. This arm is adapted to fit in a cut out 12 of the plate 5 when the 70 spindle is moved to a non-operable position and the arm acts to effectively prevent any movement of the plate 5. In addition to this arm, the spindle has wings 13 for engaging the branches 6 of the plate 5 to move 75 the latch. The exposed or outer end of the spindle has an operating handle 14 and adjacent this handle the spindle is recessed as at 15, 16, to receive a locking pin 17, the spindle when drawn in and locked with the 80 pin 17 in the recess 15, preventing any movement of the spindle into position to be engaged by the key from the outside. With the pin 17 in the recess 16 the lock latch is 85 prevented from movement because the spindle cannot be turned even though it may be reached by the key. At the other, or inner, end the spindle is kerfed, as at 18 to receive the flattened end 19 of the key shank 20 by which the spindle is turned from outside the door. 90

The control mechanism within the casing 2 includes a support 30 of plate-like form which is spaced from the lock-latch housing by an angularly disposed portion 31. The 95 construction of this support forms a way for a guard plate 32 having an aperture 33 which in one position of the plate is in alignment with the spindle 9, access to the spindle being through an aperture 33' of the support 100 30. A second aperture 34 of the guard plate receives a stud 35 of an actuating slide 36, this stud projecting through a slot 37 in the support 30. The slide is adapted to be moved by the bit of the key after tumblers 105 38 have been dislodged from locking engagement with a post 39 on the slide, the tumblers having pivotal engagement with the support 30 which also carries a guiding projection 40 for the slide 36.

At 50 I have indicated a spindle stop. This stop is mounted for turning movement on a stud 51 projecting from the housing and it has a spindle engaging finger 52 and a key 5 engaging finger 53, the latter being in a plane right angular to the finger 52. A projection 54 from the housing 2 limits the clockwise turning movement of the stop 53.

In the use of my improved lock, the lock-latch may be readily withdrawn from engagement with its keeper, as indicated in Fig. 2, by turning the handle 14, one of the wings 13 of the spindle engaging its complementary branches 6 to force the lock-latch inwardly. Assuming it is desired to prevent access of the lock-latch from the outside, with the control parts as indicated in Fig. 2, the key is inserted and its flattened end turned so that the spindle may be engaged and pushed inwardly against the tension of the spring 8, the key being then turned so that its bit will engage the finger 53 to turn the stop 50 so that finger 52 will be placed across the path of the spindle to hold the latter inwardly against the tension of spring 8. The key is now turned in an opposite direction and engaging the tumblers to move them from locking engagement with the slide 36 actuates the latter by contact with its talons 60. Movement of this slide will elevate the guard plate 32 into the position where its aperture 33 is out of line with the key spindle, as indicated in dotted lines, Fig. 3. The key is then withdrawn from the lock. It will be seen that with the control mechanism in the position stated the spindle of the lock-latch cannot be reached except by appropriate key. Even though a key may be inserted and the tumblers actuated the spindle is still out of reach and will remain so until the stop 50 is actuated to release the spindle. In the proper actuation of the parts from the outside the key is first turned so as to turn the stop 50 to release the spindle, is then given a reverse turn to engage the tumblers and actuate the slide 36 to move the guard plate 32 and bring its aperture 33 into alignment with the spindle 9. The key may now be farther inserted and its flattened end 19 will fit in the kerfed end of the spindle. Turning of the key will retract the lock-latch.

The advantages of my invention will be apparent. It will be appreciated that I have provided a simple mechanism whereby a door is effectively locked and which requires in addition to the appropriate key a certain maneuvering of the key in the lock to bring the parts into operative position.

60 I claim as my invention:

1. A door lock including a spring tensioned lock-latch, an actuating spindle therefor, a handle for operating said spindle from inside the door, said spindle being operable by a key from outside the door, means for

controlling access to said spindle, and key actuated means for actuating said last mentioned means.

2. A door lock including a spring tensioned lock-latch, an actuating spindle therefor, a handle for operating said spindle from inside the door, said spindle being operable by a key from outside the door, a guard plate having an aperture through which the key must be projected to engage said spindle, and a tumbler controlled actuating slide to shift said plate.

3. A door lock including a spring tensioned lock-latch, a rotatable and longitudinally movable actuating spindle therefor, a handle for operating said spindle from inside the door, said spindle being operable by a key from outside the door, a guard plate having an aperture through which the key must be projected to engage said spindle, a key operated stop for holding said spindle at the limit of its inward longitudinal movement and out of key-engaging position, and a tumbler controlled actuating slide for moving said guard plate into position to align its aperture with said spindle.

4. A door lock including a spring tensioned lock-latch, a rotatable and longitudinally movable actuating spindle therefor, a spring for maintaining said spindle at one limit of its longitudinal movement, a handle for operating said spindle from inside the door, said spindle being operable by a key from outside the door, a guard plate having an aperture through which the key must be projected to engage said spindle, a rotatable stop for holding said spindle against the tension of its spring and out of key-engaging position, said stop having a key engaging portion by which it may be moved to operative and inoperative position, and a tumbler controlled actuating slide for moving said guard plate to align its aperture with said spindle.

5. A door lock including a spring tensioned lock-latch, a rotatable and longitudinally movable actuating spindle therefor, a spring for maintaining said spindle at one limit of its longitudinal movement, a handle at one end of said spindle for operating it from inside the door, said spindle having a kerf in its opposite end, a guard plate having an aperture which in one position of the plate is in alignment with said kerfed end of the spindle, a rotatable stop for holding said spindle against the tension of its spring, and a tumbler controlled actuating slide for moving said guard plate to align its aperture with said spindle, in combination with a key for moving said spindle stop, actuating said tumbler controlled slide, and engaging said spindle to retract said lock-latch.

6. A door lock including a spring tensioned lock-latch, a rotatable and longitudi-

- nally movable actuating spindle therefor, a
spring for maintaining said spindle at one
limit of its longitudinal movement, a handle
at one end of said spindle for operating it
from inside the door, said spindle having a
kerf in its opposite end, a guard plate hav-
ing an aperture which in one position of the
plate is in alinement with said kerfed end
of the spindle, a rotatable stop for holding
said spindle against the tension of its spring,
a tumbler controlled actuating slide for
moving said guard plate to aline its aper-
ture with said spindle, and a stop pin for
engaging said spindle to lock it against ro-
tatable and longitudinal movement, in com-
bination with a key for moving said spindle
stop, actuating said tumbler controlled slide,
and engaging said spindle to retract said
lock-latch.
- 20 7. A door lock including a spring ten-
sioned lock-latch, having a cut away por-
tion, a rotatable and longitudinally movable
actuating spindle therefor, a laterally ex-
tending arm on said spindle adapted to be

25 moved into said cut away portion to hold
said lock latch against movement, a spring
for maintaining said spindle at one limit of
its longitudinal movement and its arm free
of said cut away portion, a handle at one
end of said spindle for operating it from in-
side the door, said spindle having a kerf in
its opposite end, a guard plate having an
aperture which in one position of the plate
is in alinement with said kerfed end of the
spindle, a rotatable stop for holding said
30 spindle against the tension of its spring and
said arm in the cut away portion of said
lock latch, and a tumbler controlled actuat-
ing slide for moving said guard plate to
aline its aperture with said spindle, in com-
bination with a key for moving said spindle
stop, actuating said tumbler controlled slide,
and engaging said spindle to retract said
lock-latch.

35 In testimony whereof I have signed this
application.

CARL HOFFMAN.
